(57) **CLAIM**

The ornamental design for a desk clock, as shown and
described.

DESCRIPTION

FIG. 1 is a front elevation view of a desk clock showing my
new design, the indicated time being shown in broken lines
for illustrative purposes only and forms no part of the
claimed design;

FIG. 2 is a side elevation view of a first side thereof;

FIG. 3 is a side elevation view of a second side thereof;

FIG. 4 is a rear elevation view thereof;

FIG. 5 is front perspective view showing the desk clock of
FIG. 1, the indicated time being shown in broken lines for
illustrative purposes only and forms no part of the claimed
design; and,

FIG. 6 is a rear perspective view thereof.
